UNITED STATES PATENT OFFICE

JOHN THOMPSON, OF BUCYRUS, OHIO, ASSIGNOR TO THE BUCYRUS FOUNDRY AND MANUFACTURING COMPANY, OF SAME PLACE.

DREDGING-MACHINE.

SPECIFICATION forming part of Letters Patent No. 341,612, dated May 11, 1886.

Application filed October 27, 1885. Serial No. 181,094. (No model.)

To all whom it may concern:

Be it known that I, JOHN THOMPSON, a citizen of the United States, and a resident of Bucyrus, in the county of Crawford and State 5 of Ohio, have invented certain new and useful Improvements in Dredging-Machines, of which the following is a specification.

My invention, showing the construction and location of the spud-operating mechanism, the 10 spuds themselves being omitted for the sake of clearness in the figures, relates to improvements in the construction and operation of the "spuds," so called, which form part of dredging apparatus, pile-drivers, and like 15 machines, they being devices employed for steadyng and holding in place the scow or float while doing its work; and it has special relation to the spuds used on dredging-machines, which are intended for ditch-digging or other 20 work in which the float will lie adjacent to a wall or bank, although also applicable in part to spuds generally, as hereinafter set forth.

In the accompanying drawings the same letters indicate the same parts in all the figures. 25 Figure 1 illustrates a top plan view of a dredging-machine embodying the invention. Fig. 2 illustrates a side elevation of one of the spuds. Fig. 3 illustrates a front elevation of one of the spuds. Fig. 4 illustrates a top plan 30 view of the spud-operating mechanism enlarged.

A is the float or scow. B is a frame erected thereon for the support of certain parts of the mechanism. C is the mast. D is the boom. 35 E E represent parts of the swinging frame which supports the boom, and which is turned by suitable draft-chains connected with a suitable drum or equivalent device. All these parts are constructed as usual in such machines, and the other necessary parts thereof are also present, many of them being illustrated in the drawings. They are not, however, except as hereinafter set forth, specifically described, since they are not material to 40 a clear understanding of the invention.

G G are two frames or uprights erected in pairs on opposite sides of the scow, preferably a little aft of the mast. They consist of strong uprights of timber or metal suitably braced, 50 which act as the ways or guides for the spud-frames to slide in. The spud frames are seen at H H. They are suitably strengthened by

cross-braces I I, and slide up and down in the frames G G.

J J are timbers or iron pieces firmly bolted to 55 the spud-frames H H, one to each side of each spud-frame. They extend downwardly and outwardly at an angle thereto, and from their lower ends other timbers or pieces of iron, K K, extend inwardly and are fastened to the 60 spud-frames H H. There are also preferably cross-braces L L, which extend from the spud-frame H H upwardly and outwardly, crossing the pieces J and K, and are firmly bolted or otherwise fastened to them. The 65 under sides of the pieces K and L are planked over. The planks are seen at M, they extending the width of the spud-frames, and as much farther as may be desired.

The side pieces, H H, of the spud-frames are 70 confined within the ways G G by plates N N, &c., bolted to the uprights G G, and extending over the pieces H H, or in any other suitable manner.

The spuds are raised and lowered by means 75 of the chains or ropes O, which are respectively fastened at one end to an upper cross-piece in the spud-frames, respectively, (seen at P,) and thence, extending downwardly, take several turns around a drum or shaft, Q, there 80 being a drum for each spud revolving in journals on the deck of the float, and the lower ends of the chains, respectively, are fastened to lower cross-pieces of the spud-frames, (seen at R.) The drums Q are turned by means of 85 worm gear-wheels S, placed on the shaft of the drums, which mesh into worms T. The worms T are rotated by chain belts U, which pass over sprocket-wheels N on the worm-shafts. The chains extend aft, and pass around pulleys 90 or sprocket-wheels W, one being provided for each chain. They are placed loosely on an extension of the shaft X of the down-haul drum Y. These pulleys W run loosely on the shaft X, and act merely as idlers until they 95 are brought up to the friction-surfaces Z Z, as hereinafter set forth.

The pulleys W are double-grooved, and from the groove not occupied by the chain belt U another chain belt, A', extends rearwardly 100 and passes around other sprocket-wheels or pulleys B', placed loosely on an extension of the shaft of the hoisting-drum C', the same as those on the shaft of the down-haul drum Y,

and these pulleys B' are also idlers until brought up to the friction-surfaces D' D'. The friction surfaces Z Z and D' D' are rigidly attached to the shafts on which they are placed, 5 and the pulleys W W and B' B' are all provided with friction-surfaces adapted to engage with them for the purposes of rotation. E is a heavy metallic plate or piece of timber, to which are connected by pivots F' F' at some 10 distance from their ends two rocking levers, G' O''. These levers at H' H', &c., engage by means of suitable pivotal connections with the pulleys W W and B' B', preferably through the hubs of these several pulleys. The levers G' O'' extend forwardly, and engage with rods I' I'', respectively, which are extended to any 15 convenient place for the workmen to operate them, where these terminate in hand-levers J' J'', which will be attached in any suitable manner to the ends of the rods I' I'' at the points marked J' J''. It will thus be seen that by operating the levers which, as stated, may be attached at the ends of the rods I' I'' shown 20 at J' J'', forward or back, as required, the several pulleys W W and B' B' will be brought to bear against the friction surfaces Z Z and D' D', respectively, and also that inasmuch as the rotation of the shaft of the hoisting-drum, 25 on which the pulleys B' B' are placed, is the reverse of that of the shaft of the down-haul drum, on which the pulleys W W are placed, the chains U will be made to travel in opposite 30 directions—in other words, the worms, and consequently the drums Q, will be turned in 35 different directions, and the spuds wound up or down, depending on whether the pulleys B' B' or W W are in contact with the respective friction surfaces; and it will also be observed that when the pulleys W W are 40 driven against their respective friction-surfaces by the levers G' and O'', respectively, the same levers will automatically carry the pulleys B' B' away from their friction-surfaces D' D'. Thus they will run loose and be 45 simply idlers supporting the chain belts A' A', and also that when the same levers are employed to force the pulleys B' B' against the friction-surfaces D' D'. By this act they remove the pulleys W W away from the friction-surfaces Z Z, and that then these pulleys 50 simply transmit the motion received from the chains A' A' to the chains U, for operating the worms.

It is obvious that instead of the chain O and 55 drum Q a pinion on the drum-shaft which engages with a rack on the spud-frame H may be used, or other equivalent device.

The operation is as follows: Assuming the 60 scow or float to be working in a ditch made by itself or in any other place adjacent to a bank against which it may receive support, so that the weight of the loaded bucket or other load will not keel the float over when 65 swung "outboard" for dumping or other purpose, the down-haul and lifting chains of the machine are slackened up or disconnected or put in such relation to their winding-drums,

respectively, by unwinding as to allow of rotation of their respective drums without jamming. Then, by means of the lever J' or J'', 70 as the case may be, depending on whether the spud to be operated is on one side or the other of the float, the pulley W or B', which is connected to the lever which is moved, will be brought into contact with the friction-surface Z or D', depending upon whether the spud is to be lowered or raised, and in this manner it will be apparent that the two spuds can be brought down upon the edge of the banks and forced down hard thereon, thus holding the 75 float firmly between them. The worm F not only moves the spud frames, but locks the same in their desired position, the pressure against the spuds not being sufficient to turn them, and thus the spuds can be elevated or 80 depressed at pleasure, and made to accommodate themselves to banks of different heights. A crank attached to the shaft of the worm T may be employed to operate the spuds by 85 hand, if desired. The side pieces, H H, of the spud-frames are carried down below the planked-up part of the spuds, so that they may be used to steady the float by contact 90 with the bottom of the ditch, where banks are not available, even if submersion of the 95 planked-up part of the spuds is necessary to attain this end.

I do not limit myself to the details of construction shown, since they may be greatly departed from and still my invention be employed.

I claim—

1. The combination, in a dredge or like machine, of spuds formed of a sliding frame having laterally-extending platform-like surfaces adapted to take a bearing on the bank of a ditch, guides for the spud-frames, and mechanism for raising and lowering the spuds, substantially as and for the purposes set forth. 105

2. The combination, in a dredge or like machine, of spuds formed of a sliding frame having laterally-extending platform-like surfaces adapted to take a bearing on the bank of a ditch, guides for the frames, and downwardly-projecting portions of the spud-frames 115 below the platform-like surfaces adapted to take a bearing on the bottom of the ditch, and mechanism for raising and lowering the spud-frames, substantially as and for the purposes set forth. 120

3. The combination of loose pulleys B' B' W W, mounted on shafts, friction-surfaces D' D' Z Z, belts U and A', means for moving the pulleys against the friction-surfaces, respectively, driving-wheels engaging with the belts 125 U, and sliding spuds operated by the driving-wheels, whereby the spuds may be forced downwardly and also elevated, substantially as and for the purposes set forth.

4. The combination of loose pulleys W W 130 and B' B', mounted on shafts, friction-surfaces D' D' and Z Z, belts A' and U, pivoted levers G' O'', hand-levers connecting with the levers G' O'', and sliding spuds caused to move up-

wardly and downwardly by engagement with the driving-belts A' and U, depending on the movement of the levers G' O'', carrying the loose pulleys W W and B' B', substantially as 5 and for the purposes set forth.

5. The combination, in a dredge or like machine, of a laterally-extending support or frame adjustable vertically relative to the bank, the outer part whereof is adapted to 10 steady the float by its impact against the bank,

and mechanism for vertically adjusting the said support or frame, substantially as and for the purposes set forth.

Signed at New York, in the county of New York and State of New York, this 23d day of 15 October, A. D. 1885.

JOHN THOMPSON.
